SPARK AND FLAME ARRESTOR

Edward L. Moran, Chicago, Ill., assignor to
Stone Wheel Inc., Chicago, Ill., a corporation of
Illinois

Application January 4, 1943, Serial No. 471,305

3 Claims. (Cl. 183—121)

This invention relates in general to a spark and flame arrestor, and particularly to a device for reducing the velocity of the exhaust of a combustion engine.

An object of this invention is to provide compact, simple and efficient means for providing a graduated reduction of the velocity of the exhaust gases, and preventing back pressure in the exhaust of a combustion engine, and the discharge of sparks and flame therefrom. A further object of this invention is to provide a safety device for combustion engines, particularly for automotive vehicles propelled by combustion engines operating in regions of relatively high fire hazard, such as powder mills, oil and gas fields, refining areas, grain fields, and other localities where inflammable materials are present, as well as in the transportation of explosive and highly combustible materials including trucks engaged in the transportation of powder, gasoline and the like, farm tractors, and other automotive vehicles subject to extraordinary fire hazards.

Additional objects, advantages and capabilities inherent in this invention will become readily apparent from the description thereof which follows.

This invention further resides in the combination, construction and arrangement of parts illustrated in the accompanying drawing, and while there is shown therein preferred embodiment of the invention, it is to be understood that the same is susceptible of modification and change without departing from the spirit of the invention.

The accompanying drawing illustrates a selected embodiments of the invention, and views therein are as follows:

Fig. 1 is a diagrammatic sketch in perspective showing the invention in place on the exhaust of an automotive combustion engine.

Fig. 2 is a view of the front end of a device embodying the invention.

Fig. 3 is a sectional view along the line 3—3 of Fig. 2.

The particular device herein disclosed for the purpose of illustrating the invention comprises a hollow body member or shell 11 preferably made of steel. The body is in the form of a cylindrical member which is elongated transversely and has substantially parallel side walls with curved upper and lower connecting walls. A plurality of perforated, spaced baffle plates 12 provided with spaced apertures 13 are welded or otherwise secured to the body. One of said baffle plates forms the rear end wall or outlet of said shell.

The front end 14 of the shell is unperforated but is provided at its upper portion with a suitable opening 17 and a longitudinally extending tubular collar 15 adapted to be fitted upon the exhaust pipe 16 of a combustion engine. The collar 15 is welded or otherwise suitably secured and sealed to the shell in axial alignment with the opening 17. In order that the collar 15 may be secured to said exhaust pipe, a longitudinal opening or slot 18 is provided in the collar, and opposed lugs 19 are secured to its periphery adjacent the slot 18, the lugs being provided with a threaded bore 20 adapted to receive a screw 21 having a head 22 and provided with a spring washer 23, the arrangement being such that upon the turning of the screw 21 the collar may be clamped upon the exhaust pipe.

The openings 13 in the baffle plates 12 are of such number and size that the aggregate area 20 of the holes of each plate will be approximately 35% of the area of the baffle plate and at least approximately twice the area of the opening 17. The baffle plates are so arranged as to partition the interior of the shell into a plurality of compartments or chambers 24 and so that the apertures of one plate or partition will be staggered with respect to those of the adjacent plate so as to interrupt the flow of exhaust gases and deflect them and thus generally prevent passage 30 of gas, sparks, or flame directly or in a straight line through more than one plate or partition. It will be readily understood that such an arrangement will cause a graduated reduction in the velocity of the exhaust gases and a corresponding reduction in their pressure to atmospheric pressure in the final compartment.

The spacing of the baffle plates 12 is such that the first section or compartment 24 will be approximately 50% larger than the others so as to provide a relatively greater and sharper reduction in the velocity of the exhaust gases in the first stage. This will substantially dissipate their heat and diminish their turbulence well in advance of their final discharge into the atmosphere and permit more gradual cooling and quieting of them in the later stages of reduction. The heat dissipating character of the perforated baffle plate construction is illustrated by the fact that 45 it has been found difficult in constructing the device to weld the rear wall or baffle plate with a blow torch.

Solid matter accompanying the exhaust gases will accumulate in the first compartment which may be emptied as occasion requires, upon de-

taching the device from the exhaust pipe and pouring the contents through the opening 17.

In a form of the invention which has proven satisfactory in practice a shell of No. 18 gauge steel $4\frac{1}{2}$ " long by $5\frac{1}{8}$ " high by $2\frac{5}{16}$ " wide with an opening or inlet $1\frac{3}{4}$ " in diameter and having a collar $1\frac{1}{8}$ " wide was provided with four baffle plates of H. & K. No. 18 gauge perforated sheet steel having apertures of $\frac{7}{16}$ " diameter with centers spaced $\frac{1}{8}$ ", and an aggregate open area of 35%. In actual use it has been found that such a device practically eliminates sparks and flame from the exhaust gases of gas engines. Indeed, so cool are the exhaust gases at the discharge end of the device that the hand may safely be placed against the outlet end of the arrestor with the engine in operation.

Changes may be made in the form, construction and arrangement of the parts without departing from the spirit of the invention, and the right is hereby reserved to make all such changes as fairly fall within the scope of the following claims.

The invention is hereby claimed as follows:

1. A spark and flame arrestor for attachment to the exhaust pipe extending from the muffler of a motor vehicle and comprising a non-circular body having spaced end plates and enclosing walls including a top and a bottom, said body being elongated longitudinally and being considerably greater in vertical length than in its transverse longitudinal direction, one of said end plates being closed but having an opening at an extreme upper end thereof to receive the exhaust pipe, the other of said end plates being provided with a plurality of holes therethrough, intermediate plates arranged interiorly of the body and spaced from said end plates and from each other to provide spaced compartments within the body, said intermediate plates having a plurality of holes therethrough, the holes in said plates being out of alignment, the holes in each plate having an area at least twice as great as the area of the exhaust pipe, and means for securing the arrestor to said pipe.

2. A spark and flame arrestor for attachment to

the exhaust pipe extending from the muffler of a motor vehicle and comprising a plurality of adjacently horizontally spaced elongated thin narrow plates having a plurality of small horizontally spaced holes extending therethrough, a closed end plate spaced a predetermined distance from an adjacent plate and having an inlet opening at the top end thereof for communication with the said exhaust pipe, and a housing encompassing said plates and in physical contact with the edges of each plate, the plates forming spaced compartments within the housing, the holes in one plate being out of alignment with the holes of an adjacent plate, the area of the small holes of each of said elongated thin narrow plates being at least twice the area of the inlet opening in the closed end plate, one of said thin narrow plates being at the end of the housing opposite the closed plate and acting as the outlet for the arrestor.

3. A spark and flame arrestor for attachment to the exhaust pipe extending from the muffler of a motor vehicle and comprising a plurality of adjacently horizontally spaced elongated thin narrow plates having a plurality of small horizontally spaced holes extending therethrough, a closed end plate spaced a predetermined distance from an adjacent plate and having an inlet opening at the top end thereof for communication with the said exhaust pipe, and a housing encompassing said plates and in physical contact with the edges of each plate, the plates forming spaced compartments within the housing, the holes in one plate being out of alignment with the holes of an adjacent plate, the area of the small holes of each of said elongated thin narrow plates being at least twice the area of the inlet opening in the closed end plate, one of said thin narrow plates being at the end of the housing opposite the closed plate and acting as the outlet for the arrestor.
